(57) **CLAIM**

The ornamental design for a work light, as shown and described.

DESCRIPTION

FIG. 1 is a perspective view of the work light of my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view thereof, illustrating the work light being rotatably moved to adjust a tilted angle thereof; and,

FIG. 9 is a perspective view thereof, illustrating two light heads being rotatably moved sideward.

The broken line disclosure represents portions of the work light which form no part of the claimed design.
